BENJAMIN E. D. STAFFORD, OF PITTSBURGH, PENNSYLVANIA, ASSIGNOR TO
FLANNERY BOLT COMPANY, OF PITTSBURGH, PENNSYLVANIA.

FLEXIBLE STAY-BOLT.

1,119,655.

Specification of Letters Patent.

Patented Dec. 1, 1914.

Application filed April 1, 1914. Serial No. 323,868.

To all whom it may concern:

Be it known that I, BENJAMIN E. D. STAFFORD, of Pittsburgh, in the county of Allegheny and State of Pennsylvania, have 5 invented certain new and useful Improvements in Flexible Stay-Bolts; and I do hereby declare the following to be a full, clear, and exact description of the invention, such as will enable others skilled in the art 10 to which it appertains to make and use the same.

My invention relates to an improvement in flexible stay bolts.

The inspection of stay bolts within fixed 15 periods is mandatory, and to inspect and test them the heads of the bolts must be exposed for tapping and turning.

With stay bolts now in use, the head of the bolt is mounted in a sleeve and is covered 20 by a cap screwed to the sleeve. The pressure of the head of the bolt against the inside of the sleeve tends to bulge or expand the latter thus causing the cap to stick. Again the formation of rust on the 25 threads connecting the cap and sleeve retards the removal of the cap, hence it is usually necessary to loosen the cap by tapping it with a hammer which frequently results in fracture or other injury to the cap or 30 sleeve. Again when the cap is stuck fast, the efforts to unscrew it, result at times in loosening up the connection between the sleeve and the outer sheet of the boiler.

The object of the present invention is to 35 provide for the quick and ready inspection of the stay bolt proper without danger of injury to the parts in which the head of the bolt is mounted, and it consists in the parts and combinations of parts as will be more 40 fully explained and pointed out in the claims.

In the accompanying drawings, Figure 1 is a view partly in side elevation and partly in section of my improvement. Fig. 2 is a 45 outer end view of the same. Fig. 3 is a view in section at right angles to the section shown in Fig. 1. Fig. 4 is a view in section of the cap, and Fig. 5 is a view in section of the head of the bolt.

50 1 represents the bolt, the head 2 of which is substantially flat on top, with its periphery or rim in the arc of a circle, the curved edge of the head joining the body of the shank of the bolt by reverse curves, as 55 shown in Figs. 1 and 5. The head rests on

a concave seat 3 formed on the inner face of the sleeve 4 and it is also provided with a driver slot 5 formed by a circular or disk shaped cutter, which produces a slot with a concave floor which is in a plane wholly 60 above the transverse center of the head so as to leave ample metal below for the support of the bolt and at the same time provide ample metal to be engaged by the driver for turning the bolt. 65

The sleeve 4 is threaded externally for attachment to a sheet of the boiler, the bore at the inner end of the sleeve being of greater diameter than the body of the bolt, and made flaring so as to permit of a free 70 lateral or rocking movement of the bolt within reasonable limits. This sleeve receives and houses the head 2 of the bolt and is provided internally as previously explained with the seat 3 formed in the arc 75 of a circle concentric with the curvature of the rim of the head, against which said head rests, and which permits of a universal movement of the head on its seat during the movements caused by the expansion and 80 contraction of the sheets to which the bolt is connected. The bore or cavity of the sleeve at the outer side of the seat 3, is of a size sufficient for the free entrance of the head of the bolt, and the sleeve is preferably 85 provided externally at its outer end with an angular rim as shown in Fig. 2 for engagement with the wrench used in attaching the sleeve to the boiler sheet.

The sleeve 4 is provided adjacent its outer 90 end with an annular shoulder 6 on which the cap 7 rests; the shoulder 6 being sufficiently within the sleeve so that when cap 7 is on its seat, it will not project beyond the outer end of the sleeve. This cap forms a 95 steam tight closure for the outer end of the sleeve and is held in place by the plug 8 screwed into the ring 9. This ring is provided with two oppositely disposed ears 10 and 11, the ear 10 of which is perforated 100 for the passage of a screw bolt 12 which passes through the ear 10 and into ear 13 and forms the pivot on which the ring turns, while the ear 11 is provided with an open slot for the reception of the screw bolt 14. 105 The ring is therefore pivoted to the bolt 12 and is free to swing laterally thereon, while the bolt 14 serves to hold the ring in position over the end of the sleeve, and assists in supporting the ring against the outward 110

thrust of the plug. The ring is further supported in its assembled position by the overhanging lip 15 engaging the projecting flange 16 on the ring.

5 When the parts are assembled, the plug 8, which is threaded externally, is turned by a suitable tool inserted in the angular recess in the outer face, in a direction to engage and bear against the cap thus forcing the latter solidly against its seat and tending to force the ring outwardly against the heads of the bolts, thus not only locking the cap in place but also locking the ring against the possibility of any turning movement on its pivot bolt 12. When it is desired to inspect the bolt head, the plug 8 is withdrawn sufficient to relieve all pressure against the cap, and if necessary the bolts 12 and 14 or either of them, may be unscrewed sufficiently 10 to free the ring. This relieves all friction between the ring and its screw bolts 12 and 14 and leaves the ring free to be turned, and after the latter has been turned to one side and out of the plane of the long axis of the 15 bolt, the cap 7 which is then unconfined is free to be removed. After the inspection the cap is replaced, the ring turned to its normal position and the parts again locked by screwing in the plug and screwing up on the bolts 12 and 14.

It is evident that changes in the construction and relative arrangement of the several parts might be made without avoiding my invention and hence I would have it understood that I do not restrict myself to the particular construction and arrangement of parts shown and described, except as required by the scope of the claims.

Having fully described my invention what 40 I claim as new and desire to secure by Letters-Patent, is:

1. In flexible stay bolt construction, the combination of a sleeve, a cap seated within the sleeve and closing the outer end of the latter, a ring pivoted to the sleeve at one side of the latter, the axis of said pivot being parallel with the long axis of the

sleeve, means on the opposite side of the sleeve for engaging the ring when the latter is in its normal position, and a screw plug 50 carried by the ring and adapted to engage the cap.

2. In flexible stay bolt construction, the combination of a sleeve, a cap seated within the sleeve, a ring mounted on the outer end 55 of the sleeve and provided adjacent its outer edge with a hole and at a diametrically opposite point with an open slot, a bolt passing through the hole in the ring and secured to the sleeve, a bolt secured to the sleeve and 60 adapted to rest in the slot in the ring when the latter is in its normal position, and a screw plug carried by said ring and adapted to be forced inwardly into contact with the cap. 65

3. A stay bolt the head of which is rounded and provided with a drive slot formed in the arc of a circle, the said slot being wholly to one side of the transverse center of the head, substantially as and for the purpose 70 described.

4. In flexible stay bolt construction, the combination of a sleeve, a ring pivoted to the sleeve, the axis of the pivot being in the direction of the long axis of the sleeve and 75 a screw plug carried by the ring and adapted to normally rest in line with the outer end of the sleeve.

5. In flexible stay bolt construction, the combination of a sleeve, a ring pivoted to 80 the sleeve, the axis of the pivot being at one side of the long axis of the latter, means at the opposite side of the sleeve for engaging the ring when the latter is in its normal position, and a screw plug carried by 85 the ring and movable toward and away from the outer end of the sleeve.

In testimony whereof, I have signed this specification in the presence of two subscribing witnesses.

BENJAMIN E. D. STAFFORD.
